US00D915210S

(12) **United States Design Patent** (10) **Patent No.:** **US D915,210 S**
(45) **Date of Patent:** **** Apr. 6, 2021**

(54) **CONTAINER**

(71) Applicant: **John Hegarty**, Thurles (IE)

(72) Inventor: **John Hegarty**, Thurles (IE)

(73) Assignee: **AQUA STORAGE RETAINERS LIMITED**, Thurles (IE)

(**) Term: **15 Years**

(21) Appl. No.: **29/721,513**

(22) Filed: **Jan. 21, 2020**

Related U.S. Application Data

(63) Continuation-in-part of application No. 29/721,509, filed on Jan. 21, 2020.

(30) **Foreign Application Priority Data**

Jul. 19, 2019 (EM) 006638573

(51) LOC (13) Cl. **09-01**

(52) U.S. Cl.

USPC **D9/527; D9/528**

(57) **CLAIM**

The ornamental design for a container, as shown and described.

DESCRIPTION

FIG. 1 is a front-top-right perspective view of a container showing my new design;

FIG. 2 is a front-top-left perspective view thereof;

FIG. 3 is a front-bottom-left perspective view thereof;

FIG. 4 is a front elevational view thereof;

FIG. 5 is a rear elevational view thereof;

FIG. 6 is a top plan view thereof;

FIG. 7 is a bottom view thereof;

FIG. 8 is a right-side elevational view thereof; and,

FIG. 9 is a left-side elevational view thereof.

The broken lines showing of tap in FIGS. 1, 3-5 and 7-8 are included for the purpose of showing environmental structure and form no part of the claimed design.

1 Claim, 9 Drawing Sheets
